TYPOGRAPHICAL DISTRIBUTING MACHINE

Norman Dodge, Garden City, N. Y., assignor to
Mergenthaler Linotype Company, a corpora-
tion of New York

Application December 16, 1931
Serial No. 581,340

22 Claims. (Cl. 199—39)

This invention is directed to certain improvements in the distributing mechanism of a typographical machine such as that disclosed in the pending application to D. S. Kennedy, Serial No. 578,632, filed December 3, 1931, and wherein the matrices handled include not only regular matrices of standard length but also special matrices of a much greater length. In this machine, the matrices, preparatory to distribution, are detached from the composed line and fed successively to the distributor by a reciprocating finger which cooperates with the lower edges of the matrices and is capable of vertical adjustment to compensate for their difference in the length. Matrices released by the distributor are conducted to their respective magazines by one or the other of two magazine entrances which are rotatably mounted so that either may be brought into operative position as desired. The partitions of one of these entrances are of the usual length or height to cooperate with the regular matrices, and the partitions of the other entrance are shorter or lower to cooperate with the longer special matrices.

The present invention aims to simplify the above arrangement and contemplates primarily the use of a single magazine entrance which will take care of both the regular and special matrices irrespective of their difference in length. To this end, the partitions of the improved entrance are made extensible so that they may be increased or decreased in length or height according to the length of the particular matrices in use. In the preferred embodiment illustrated, the partitions consist of fixed lower sections and movable upper sections carried by an adjustable holder which may be raised and lowered as desired to locate said upper sections at the proper distance from the distributor bar.

The invention also provides a matrix feeding device which will be capable of handling the long and short matrices without adjustment or manual attention.

The exact construction, arrangement, and operation of the parts will best be understood from the detailed description to follow.

In the accompanying drawings, the invention has been shown merely in preferred form and by way of example, and as applied to a particular kind of machine, but obviously many changes and variations may be made therein and in its mode of application which will still be comprised within its spirit. It should therefore be understood that the invention is not limited to

any specific form or embodiment except in so far as such limitations are specified in the claims.

Referring to the drawings:

Fig. 1 is a side elevation of the upper portion of a linotype machine showing the partitions of the improved magazine entrance extended to cooperate with the short regular matrices;

Fig. 2 is a similar view showing the partitions collapsed or unextended to cooperate with the longer special matrices;

Fig. 3 is an enlarged top plan view of the parts shown in Fig. 1, the distributor being omitted;

Fig. 4 is a vertical section taken through the improved magazine entrance and showing details of construction thereof;

Fig. 5 is a front elevation taken on the line 5—5 of Fig. 4;

Fig. 6 is a detail vertical section taken on the line 6—6 of Fig. 3;

Fig. 7 is a rear elevation of the distributor box 75 and parts associated therewith;

Fig. 8 is a vertical section taken on the line 8—8 of Fig. 7; and

Fig. 9 is a vertical section taken on the line 9—9 of Fig. 7.

As shown in Fig. 1, the machine is equipped with three superposed magazines A¹, A², A³, mounted for vertical movement in the machine frame so that any selected one may be brought into the operative position as desired. The two lower magazines A², A³ are adapted to contain sets of regular matrices X, which are formed as usual with the upper and lower projecting ears x¹, x²; whereas, the upper magazine A¹ is adapted to contain a set of special matrices Y, which, though longer than the regular matrices, are otherwise similar thereto, being of the same width and formed with like upper and lower projecting ears y¹, y².

When a line of the matrices X or Y during its circulation through the machine is lifted by the so-called "second elevator" (not shown) to the distributing level, it is immediately transferred therefrom through a distributor box B (see Fig. 7) and up against stop shoulders B¹, B², B³, which are disposed in pairs and formed on extensions B⁴ of the box rails B⁵. The box B is arranged, as usual, at the receiving end of the distributor proper which, as shown in Figs. 1 and 2, comprises the single distributor bar D and the associated set of three (two upper and one lower) distributor screws D¹.

The uppermost pair of stop shoulders B¹ cooperate with the upper projecting ears of both the regular matrices X and the special matrices

Y, whereas the two lower pairs of stop shoulders B², B³, cooperate respectively with the lower projecting ears of said matrices. The several pairs of stop shoulders are vertically aligned with one another and are arranged to arrest the leading matrix of the line in operative relation to a reciprocating finger C, which latter is adapted to lift the matrices, one after another, above the stop shoulders and into the range of action of the distributor screws. As the matrices enter the distributor, they are advanced by the screws across the rail extension B⁴ into engagement with the bar D and thence along the same until released above their respective magazine channels. 15 The lower distributor screw D¹, as in the Kennedy application above referred to, is considerably larger in diameter than its companions and is spaced a predetermined distance below them so as to cooperate with the lower projecting ears 20 of both the regular matrices X and the special matrices Y (compare Figs. 1 and 2).

According to the present invention, the finger C is arranged to lift the matrices X and Y by their upper projecting ears, instead of by their 25 bottom edges, the upper ears of both the regular and special matrices, as before stated, being adapted to occupy the same position against the stop shoulders B¹ preparatory to their delivery to the distributor. As best shown in Figs. 7 and 30, the finger C is slidably mounted for vertical movement in a bracket plate B⁶, which latter is secured to the rear wall of the distributor box B and is formed with a tongue b which engages in a corresponding slot c formed in the finger C. 35 The body portion of the finger C (see Fig. 9) is aligned with the rear wall of the box B and is provided with a vertical rib or lip c¹ arranged directly in front of the contiguous stop shoulder B¹, so as to engage the upper ears x¹ or y¹ on the 40 rear edges of the matrices X and Y. The thickness of the lip c¹ is made less than that of the thinnest matrix to be distributed so as not to engage more than one matrix at a time. In the lower position of the finger C, the top edge of the 45 lip c is caused to occupy a position immediately below the rails B⁵ in order to permit the upper ears of the leading matrix of the line to engage against the stop shoulders B¹, and in the upper position of the finger, the top edge of the lip c is 50 caused to occupy a position slightly above said stop shoulders (see Fig. 7) in order that the lifted matrix may be pushed off the lip under the pressure applied at the opposite end of the line and obtain support upon the corresponding rail extensions B⁴.

Operation of the finger C is effected by a constantly rotated edge cam D² through the medium of a vertical reciprocating plunger C¹ to which the finger is fastened. The plunger C¹ (see Figs. 66 7 and 8) is mounted in a suitable bearing B⁷ and provided at its upper end with an anti-friction roller C² which is held resiliently engaged with the cam D² by a pull spring C⁴, the latter being arranged alongside the bearing B⁷ and attached 65 to the lower end of the plunger C¹. The cam D² is mounted on one of the distributor screw spindles D³ (Fig. 7) and is adapted, during each rotation of the distributor screws D¹, first to depress the plunger against the tension of the 70 spring C⁴ and then to allow it to rise under the influence of said spring. While the purchase of the lip c¹ is obtained at one corner only of the individual matrices, the side walls of the distributor box B (see Fig. 8) are sufficiently high to 75 sustain them edgewise in perfect upright posi-

tion as they are lifted above the stop shoulders B¹, B² and B³. Any danger of the matrices tilting or slipping off the lip c¹ is thus obviated and the finger is allowed to function in the manner required.

As the matrices X or Y are released from the distributor bar D, they are conducted to their appropriate magazine by a single magazine entrance E, the latter (see Fig. 4) comprising a front plate E¹, a curved back plate E², and a series of intermediate partitions E³ which divide the entrance into a corresponding series of matrix channels aligned with the magazine channels. The entrance E is mounted on a horizontal supporting frame F and locked thereto in the usual way by means of a clamping bar F¹ arranged to cooperate with ears e formed on the partitions E³. The frame F (see Figs. 1 and 2) is provided with upright side members F², F³, which are hingedly mounted at their lower ends on a horizontal axis o in fixed side brackets O of the main frame, so that the entrance E may be swung back and forth when access to the magazines is desired. A pull spring F⁴ connected to the side member F² facilitates these operations and serves to hold the entrance against stop screws o¹ in its normal or upright position (see Fig. 1). The stop screws o¹, as shown in Figs. 1 and 3, are mounted in subsidiary brackets O¹ secured to the main brackets O, and are arranged to engage the side members F², F³ of the frame F.

In adapting the magazine entrance E to the matrices X and Y, the partitions E³ thereof, under the present invention and as best shown in Figs. 4 and 5, are made up respectively of 110 fixed lower sections E⁴ and movable upper sections E⁵, the latter being adjustable vertically to increase or decrease the height or length of the partitions according to the particular matrices in use. That is to say, when changing 115 from the special matrices Y to the regular matrices X, or vice versa, the upper sections E⁵ of the partitions E³ are moved upwardly or downwardly to extend or collapse the partitions a distance corresponding to the difference in length 120 of said matrices, it being understood that the clearance permitted in practice between the upper edges of the partitions and the lower ends of matrices suspended from the distributor bar, is limited to a few thousandths of an inch in 125 order to insure their passage uninterruptedly into the entrance channels as they are released from the bar.

The fixed lower sections E⁴, in the preferred embodiment illustrated, are much longer or 130 higher than the upper sections E⁵ and have their upper ends permanently located the proper distance below the distributor bar D to cooperate with the special matrices Y. The upper sections E⁵ are therefore devoted to the regular 135 matrices X and when raised into action constitute, in effect, upper extensions of the lower sections E⁴.

To permit the adjustments of the upper sections E⁵ (see Fig. 4), they are mounted by 140 means of projecting ears e¹, e² in vertical slots e³ formed in the front and rear plates E¹, E² of the entrance E. The ears e¹ project through the front plate E¹ and are connected thereto by an anchor rod e⁴; whereas, the ears e² project 145 through the back plate E² and are hooked over horizontal ribs g of an auxiliary frame or holder G, which extends alongside the rear face of the entrance E and is slidably mounted for vertical movement in the rocking frame F.

The holder G (see Fig. 3) is provided at its opposite ends with wear shoes G¹ and between its ends with a bar G² for locking the movable sections E⁵ of the partitions E³ to the ribs g. Like the bar F¹, the bar G² is hingedly mounted (Figs. 3 and 4) on pins g¹ and held firmly engaged with the ears e² by clamping screws g². The shoes G¹ of the holder G fit into corresponding vertical guideways F⁵ which are formed in the upright side members of the rocking frame F and allow the holder to be raised and lowered to carry the upper sections E⁵ of the partitions into their active or inactive position. A pair of stop pins g³ (Fig. 6), mounted transversely in the side members F², F³ of the frame F and arranged directly below the wear shoes G¹, limit the downward movement of the holder G, and serve to locate the upper sections E⁵ in their inactive position with their upper edges flush or slightly below the upper edges of the lower fixed sections E⁴ (see dotted lines, Fig. 4). A second pair of pins g⁴, similarly mounted in the side members F², F³ and arranged above the wear shoes, merely prevent the accidental disengagement of the holder from the guideways F⁵, being located at such distance above the shoes G¹ that the latter will stop short of them when the holder G is raised to locate the upper sections E⁵ in their active position.

Operation of the holder G is effected by a fore-and-aft hand lever H arranged conveniently at the front of the machine and pivotally mounted on the axis o of the rocking frame F. The lever H (see Fig. 1) is connected to the holder G through the medium of a rock shaft J which is journalled at its opposite ends in the upright side members F², F³, and provided with a crank arm J¹ extending forwardly from one end of the shaft so as to cooperate with a sector plate H¹ secured to the rear arm of the hand lever H. The sector plate H¹ is located directly beneath the crank arm J¹ and formed with a concentric track portion H², the purpose of which will presently appear. The rock shaft J is also provided with a pair of parallel arms J² arranged between the side members of the frame F and loosely connected to corresponding screws studs g⁵ which are mounted in holder G at the opposite ends thereof (see Fig. 3).

The parts are so arranged that, when the hand lever H is swung downwardly, the sector plate H¹ will cam the crank arm J¹ upwardly and through the rock shaft J and the parallel arms J², raise the holder G in the guideways F⁴. As the lever H approaches the limit of its downward movement, which is determined by a fixed stop pin o² (Fig. 1), the concentric track portion H² of the sector plate H is brought beneath the front end of the crank arm J¹, and the holder G is thus locked in its uppermost position and its weight transmitted directly to the axis o. This operation extends the partitions E³ of the magazine entrance, i. e., the movable sections E⁵ are raised to locate their upper edges at the proper distance below the distributor D to cooperate with the regular matrices X (see Fig. 1). Should access to the magazine at this time be desired, the supporting frame F may be swung freely back and forth to and from the position indicated in dotted lines (Fig. 1) without disturbing the position of the holder G, the crank arm J¹ at such time being adapted to ride upon the concentric track portion H² of the sector plate H¹.

When now the hand lever H is swung upwardly,

the track portion H² is first moved from beneath the crank arm J², and the holder G is then allowed to slide downwardly in the guideways F⁵ under the control of the sector plate H¹. The partitions E³ are thus collapsed or restored to their unextended condition, i. e., as shoes G¹ of the holder engage the stop pins g³, the movable sections E⁵ of the partitions will be lowered to leave the upper edges of the lower fixed sections E⁴ to cooperate with the special matrices Y (see Fig. 2). Under the latter adjustment of the parts, the position of the holder G will likewise remain unchanged when the entrance E is rocked backwardly for access to the magazines, since the weight of the holder is far greater than the resistance presented thereto by the lever H. In other words, the hand lever H in the lower position of the holder G is adapted to yield and will be rocked idly about its pivotal axis by the crank arm J¹ as the frame F is swung to and fro.

Having thus described my invention, what I claim is:

1. In a typographical distributing machine adapted to be equipped with a set of matrices of one length, or a set of matrices of greater length, the combination of a distributor adapted to handle both sets of matrices, and a single magazine entrance adjustable to cooperate with either set of matrices for conducting them from the distributor to their respective magazines.
2. A combination as specified in claim 1, characterized by the fact that the distributor therein recited consists of a single distributor bar and a set of matrix conveying screws.
3. In a typographical distributing machine adapted to be equipped with a set of regular matrices of standard length, or a set of special matrices of greater than standard length, the combination of a distributor adapted to handle both sets of matrices and comprising a single distributor bar and a set of two upper and one lower distributor screws, and a single magazine entrance adjustable to cooperate with either the regular or the special matrices for conducting them from the distributor to their respective magazines.
4. In or for a typographical distributing machine adapted to be equipped with a set of matrices of one length, or a set of matrices of greater length, a magazine entrance comprising a front plate, a back plate and a series of intermediate partitions which divide the entrance into a corresponding series of channels, said partitions being capable of extension to compensate for the difference in length of the two sets of matrices.
5. In or for a typographical distributing machine adapted to be equipped with a set of matrices of one length, or a set of matrices of greater length, the combination of a magazine entrance comprising a front plate, a back plate, and a series of intervening extensible partitions, and means for extending or collapsing the partitions to increase or decrease their length according to the particular set of matrices in use.
6. In or for a typographical distributing machine, a magazine entrance comprising a front plate, a back plate, and a set of intervening extensible partitions, the said partitions being made up of fixed lower sections and upper sections adjustable relatively thereto.

7. In a typographical distributing machine adapted to be equipped with a set of matrices of one length, or a set of matrices of greater length, the combination of a magazine entrance comprising a front plate, a back plate, and a series of intervening vertical partitions made up of fixed lower sections and movable upper sections, a holder to which the upper sections are attached, and means for adjusting said holder upwardly and downwardly to adapt the entrance to cooperate with either set of matrices. 80
8. In a typographical distributing machine adapted to be equipped with a set of matrices of one length, or a set of matrices of greater length, the combination of a magazine entrance comprising a front plate, a back plate, and a series of intervening vertical partitions made up of fixed lower sections and upper sections movable relatively thereto, a frame upon which the magazine entrance is supported, a holder for the upper sections adjustably mounted in said frame, and means for adjusting the holder upwardly or downwardly to adapt the entrance to cooperate with either set of matrices, as desired. 85
13. 9. A combination as specified in claim 8, characterized by the fact that the said adjusting means is controlled by a hand lever arranged conveniently at the front of the machine. 90
10. In a typographical distributing machine adapted to be equipped with two magazines, one containing a set of matrices of one length and the other containing a set of matrices of greater length, the combination of a distributor, a single magazine entrance having a series of partitions made up of fixed lower sections and adjustable upper sections to cooperate with either set of matrices, a supporting frame for the magazine entrance pivoted to the main frame so that it may be swung back and forth for access to the magazines, and means for maintaining the upper sections of the partitions in their adjusted positions during the pivotal movement of said supporting frame. 100
11. In a typographical distributing machine adapted to be equipped with a set of matrices of one length, or a set of matrices of greater length, the combination of a magazine entrance comprising a front plate, a back plate, and a series of intervening vertical partitions made up of fixed lower sections and upper sections movable relatively thereto, a holder for the upper sections adjustably mounted in said frame, a rock shaft connected to the holder, and means for rotating the rock shaft to move the holder and the upper sections of the partitions upwardly or downwardly to different positions of adjustment according to the particular set of matrices in use. 110
12. A combination as specified in claim 11, characterized by the fact that the said rotating means consists of a hand lever, and including means associated with the hand lever for sustaining the holder in its upper position of adjustment. 115
13. In a typographical distributing machine adapted to be equipped with a set of matrices of one length formed with upper and lower projecting ears, or a set of matrices similar in form but of greater length, the combination of a distributor adapted to handle matrices of either set, means common to both sets of matrices for sustaining them by their upper projecting ears in operative relation to the distributor, and means also common to both sets of matrices and arranged to cooperate with the upper projecting ears of said matrices for feeding them, one after another, to the distributor. 120
14. In a typographical distributing machine adapted to be equipped with a set of matrices of one length formed with upper and lower projecting ears, or a set of matrices similar in form but of greater length, the combination of distributing mechanism for handling matrices of either set and including a distributor bar and a set of two upper and one lower distributor screws, a distributor box through which the matrix lines are advanced for distribution, a pair of rails common to both sets of matrices for sustaining them by their upper projecting ears in said box, shoulders formed on the rails for arresting the leading matrix of a line at the receiving end of the distributor, and a reciprocating finger arranged to cooperate with the upper projecting ears of the matrices for lifting them one after another above said shoulders into the range of action of the distributor screws. 125
15. In a typographical distributing machine adapted to be equipped with a set of regular matrices of standard length, or a set of special matrices of greater than standard length, the combination of distributing mechanism for handling the matrices of either set including a single distributor bar and a set of matrix conveying screws, and a reciprocating member for feeding the matrices of either set successively to the distributor screws, said member being arranged to operate in a fixed zone located in definite relation to a point on the matrices common to those of both sets, for the purpose described. 130
16. A combination as specified in claim 14, characterized by the fact that the lower distributor screw is of greater diameter than its companions and is spaced below the distributor bar at a distance corresponding to the difference in length between the regular and special matrices. 135
17. In a typographical distributing machine adapted to be equipped with a set of matrices of one length formed with upper and lower projecting ears, or a set of matrices similar in form but of greater length, the combination of distributing mechanism for handling the matrices of either set and including a distributor, a distributor box through which the matrices of either set are advanced toward the bar, and means for feeding the matrices one after another to the distributor bar, said means comprising a vertical reciprocating plunger and a finger attached thereto and arranged to engage the upper projecting ears of said matrices. 140
18. A combination as specified in claim 17, including a spring connected to the plunger, and a constantly rotated edge cam for actuating the plunger against the tension of said spring. 145
19. In a typographical distributing machine adapted to be equipped with matrices formed with upper and lower projecting ears, the combination of distributing mechanism including a distributor bar, a distributor box through which the matrices are advanced toward the bar, a finger associated with the box and arranged to lift the individual matrices by one of their projecting ears, and means for sustaining the matrices edge-wise in upright position as they are being lifted. 150
20. In a typographical distributing machine adapted to be equipped with two interchangeable magazines, one containing a set of regular matrices of standard length and the other containing a set of special matrices of greater than standard length, the combination of a distributor, a single magazine entrance adjustable to cooperate with the matrices of either set for conducting them to their respective magazines, a distributor

box located at the receiving end of the distributor, and a reciprocating finger associated with the box and arranged to cooperate with the upper projecting ears of the matrices for feeding them, one after another, to the distributor.

21. In a typographical distributing machine adapted to be equipped with two interchangeable magazines, one containing a set of regular matrices of standard length and the other containing a set of special matrices of greater than standard length, the combination of a distributor comprising a single distributor bar and a set of two upper and one lower distributor screws, a distributor box located at the receiving end of the distributor, and a reciprocating finger associated with the box for lifting the regular or the special matrices, one after another, into the range of action of the distributor screws, the said finger being arranged to cooperate with the upper projecting ears of the matrices, and the lower screw of the distributor being larger in diameter than its companions so as to cooperate with both the regular and the special matrices.
